UNITED STATES PATENT OFFICE.

LEO KLEINMAN, OF NEW YORK, N. Y.

SAFETY-COCK.

1,238,023.

Specification of Letters Patent. Patented Aug. 21, 1917.

Application filed September 8, 1915. Serial No. 49,489.

To all whom it may concern:

Be it known that I, LEO KLEINMAN, residing at New York, in the county of New York and State of New York, have invented 5 certain new and useful Improvements in Safety-Cocks, of which the following is a specification.

This invention relates to a safety cock for use in controlling a flow of combustible 10 or other fluid.

The construction illustrated in the drawings, and hereinafter described, is particularly adapted for use as a controlling valve or cock for a gas stove, though obviously 15 the same may be employed for other purposes as desired.

One of the objects of this invention is to provide a combined operating handle and locking member formed of a single integral 20 piece of material, preferably sheet metal stamped out in the required shape, and further to provide a separately formed cold handle grip secured to the handle portion of the locking member by means which will 25 preclude its accidental detachment, and which means will at the same time be readily releasable to detach the handle grip when required, and which means will retain the handle in a rigid given position when 30 in use.

Other objects and aims of the invention, more or less specific than those referred to above, will be in part obvious and in part 35 pointed out in the course of the following description of the elements, combinations, arrangements of parts and applications of principles, constituting the invention; and the scope of protection contemplated will be indicated in the appended claims.

40 In the accompanying drawings which are to be taken as a part of this specification, and in which I have shown a merely preferred form of embodiment of the invention:

45 Figure 1 is a side elevational view of a gas cock, a portion thereof being shown in section for disclosing structural details;

Fig. 2 is a top plan view of the structure illustrated in Fig. 1; and

50 Figs. 3, 4, 5 and 6 are enlarged transverse sectional views taken, respectively

upon the plane of lines III, IV, V and VI of Fig. 1.

Referring to the drawings for a detailed description of the structure illustrated, the 55 reference character L indicates the body of the gas cock. This may be of any desired shape or proportions and is fitted with the usual plug 1, common to gas valves and the like, the body being provided with shoulder 60 portions 2 for engagement by a pin 3 to limit movement of the plug in open and closed position. The body is further formed with a slot 4 at its upper end.

The reference character G indicates the 65 locking member. This is formed preferably as a stamping of sheet metal and comprises a body portion or main part 5, a locking portion or latch 6, and a handle portion or stem 7.

The body portion 5 is received between 70 a pair of spaced lugs 8 upstanding from the upper end of the plug 1, and being pivotally connected thereto by a pivot pin 9 extending through said lugs and through 75 the body portion 5.

The locking portion 6 depends from the body portion 5, partly within a groove 10 formed in the plug 1, and is adapted, when the plug is closed, to have its lower end 80 engaging within the slot 4 formed in the body L, and when the valve is open, to have its lower end ride freely over the upper annular edge surface of the body L.

The handle portion 7 projects substantially horizontally from the body portion 5 and is preferably tapered toward its outer end, the extreme end portion being threaded, as at 11, to receive a binding nut 12. Where the handle portion 7 joins the body 90 portion 5, a pair of shoulders 13 are provided facing toward the threaded portion 11.

The handle grip H is preferably formed of wood turned to proper contour and formed with a central bore 14 extending 95 throughout the length thereof, and the walls thereof being normally of circular formation and opposite sides thereof being normally parallel throughout their length, that is, such a bore as can be made by an 100 ordinary revolving bit. The diameter of the bore is made of the same measurement

as the width of the stem portion 7 at a point spaced from the shoulders 13, for instance at the point designated by the line V, the relative proportions at this point being illustrated in Fig. 5 of the drawings.

The taper of the stem portion 7 enables ready and convenient insertion of the smaller end thereof into the bore of the handle grip, and the increasing width of said portion 7, between the lines V and IV, will be accommodated, when the handle grip is forced toward the shoulders 13, by the material of the handle grip being compressed to form grooves 15 at opposite sides of the bore for receiving the increasing width of the portion 7, as indicated in Fig. 4. The stem portion 7 is rectangular in cross section and the longitudinal corners thereof form biting edges for readily entering the material of the handle grip. Of course, other longitudinally extending biting edges might be provided, if found necessary. The manner of forming the grooves 15 will produce a tight fit of the handle grip upon the portion 7 and the presence of the grooves will greatly resist tendency of the handle grip to rotate upon the portion 7.

In order to further retain the handle grip against rotation, and at the same time improve the appearance of the device, a ferrule 16 is fitted over the end of the handle grip, and this is formed with a rectangular opening 17 of just the proper size to fit snugly about the portion 7 at the shoulders 13. The ferrule itself may be retained against rotation on the handle grip by any suitable means, for instance by the struck in portions 18 engaging within the material of the handle grip.

In order to retain the handle grip in place upon the portion 7, the bore thereof is enlarged at its outer end to provide an annular shoulder 19 against which portions of the clamp nut 12 engage to force the handle grip to position with the ferrule 17 against the shoulders 13.

In order to support the outer end of the handle grip, where the walls of the bore 14 are spaced from the smaller outer end of the portion 7, as shown in Fig. 6, the clamp nut 12 is provided with an extension 20 closely fitting between the walls of the bore. This extension may be tapered, as indicated, if desired, so as to facilitate its introduction into the bore and insure closer and more rigid engagement with the walls of the bore.

The clamp nut 12 is entirely received within the bore of the handle grip so that likelihood of accidental rotation thereof by contact with the hand of an operator is avoided.

It will be apparent from the above that the member G is rigid in all its parts, that it may be stamped from a single piece of sheet metal and therefore be cheap to manu-

facture and easy to assemble, and further that when the handle grip is applied thereto, there is no possible relative movement between the handle grip and the member G such as might induce creeping of the clamp nut 12 to loosen the handle grip from its intended rigid connection with the member G.

A suitable compression spring 21 is arranged between the lugs 8 and disposed for engaging between the plug 1 and an under surface portion of the body 5 of the member G to swing the member G normally so that the locking part 6 thereof will enter the slot 4 in the body L.

The body 5 is also formed with a lug 22 depending therefrom spaced from the part 6 and arranged for engaging against the upper surface of the plug 1 for positively limiting the movement of the member G when the part 6 is in a position free of the slot 4. The spring 21 is arranged between the parts 6 and 22 and is concealed from view on two sides thereby while the lugs 8 conceal it from the other two sides.

As many changes could be made in this construction without departing from the scope of the following claims, it is intended that all matter contained in the above construction or shown in the accompanying drawings shall be interpreted as illustrative only and not in a limiting sense.

Having thus described my invention what I claim as new and desire to secure by Letters Patent, is:

1. In a device of the class described, the combination with a body portion having a rotary valve therein rotatable into two positions, said rotary valve having a pair of spaced lugs upstanding therefrom, of means for locking said rotary valve in one of its two positions comprising a member formed with a main part disposed between said lugs and being pivotally connected thereto, said main part being formed with a part depending therefrom, comprising a latch, said main part being also provided with a part extending laterally therefrom, comprising a handle part, said main part being also formed with a limiting stop depending therefrom between the upstanding lugs of the rotary valve spaced from the latch part for engaging a surface portion of said rotary valve, said latch, said handle portion, and said limiting stop being formed integrally with said main part from a single piece of sheet metal of substantially uniform thickness, the valve body being formed with a slot therein into which the lower end of the latch engages when the valve is rotated to one position, the valve body being also formed with a smooth annular surface adjacent said slot along which the latch freely slides, when the valve is moved into another position, and a spring carried by

- the rotary valve interposed and concealed on two sides between the lugs on said rotary valve and being interposed and concealed on the remaining two sides between 5 the latch and the limiting stop and engaging between the rotary valve and the under surface of the main part between the latch and the limiting stop to urge the latch into latching position.
- 10 2. In a device of the class described, the combination with a body portion having a rotary valve therein rotatable into two positions, and said rotary valve having a pair of spaced lugs upstanding therefrom, of 15 means for locking said rotary valve in one of its two positions comprising a member formed with a main part disposed between said lugs and being pivotally connected thereto, said main part being formed with a 20 part depending therefrom, comprising a latch, said main part being also provided with a part extending laterally therefrom, comprising a handle part, said main part being also formed with a limiting stop depending therefrom between the upstanding lugs of the rotary valve spaced from the latch part for engaging a surface portion of 25 said rotary valve, said latch, said handle portion, and said limiting stop being formed 30 integrally with said main part from a single piece of sheet metal of substantially uniform thickness, the valve body being formed with a slot therein into which the lower end of the latch engages when the valve is rotated 35 to one position, the valve body being also formed with a smooth annular surface adjacent said slot along which the latch freely slides when the valve is moved into another position, a spring carried by the 40 rotary valve interposed and concealed on two sides between the lugs on said rotary valve and being interposed and concealed on the remaining two sides between the latch and the limiting stop and engaging between the 45 rotary valve and the under surface of the main part between the latch and the limiting stop to urge the latch into latching position, the handle part being tapered toward its outer end away from the main part, and being 50 smaller at its juncture with the main part than the width of the main part so as to provide a shoulder at the inner end of the handle part, a handle grip having a bore telescoping over said handle part, and clamping 55 means adjustably engaging between the handle grip and the outer end of the handle part to clamp the inner end of the handle grip against said shoulder.
3. A handle for valves and the like, comprising a stem projecting from the valve, and a handle grip having a bore therein telescoping over said stem, said stem being tapered toward its outer end, the bore of the handle grip being of a width less than the 60 width of the inner end of the stem and greater than the width of the outer end of the stem, the outer end of the stem being screw threaded, a nut adjustably engaging said screw threaded end having a part engaging an outer end surface portion of the 70 handle grip to force the handle grip into telescoping relation over that portion of the stem which is wider than the width of the bore of the handle grip, to support the inner end of the handle grip, and said nut having 75 a sleeve formed thereon engaging closely within the outer end of the bore of the handle grip to support the outer end of the handle grip.
4. A handle for valves and the like, comprising a stem projecting from the valve, and a handle grip having a bore therein telescoping over said stem, said stem being tapered toward its outer end, the bore of the handle grip being of a width less than the 80 width of the inner end of the stem, the outer end of the stem being screw threaded, a nut adjustably engaging said screw threaded end having a part engaging an outer end surface portion of the handle grip to force 85 the handle grip into telescoping relation over that portion of the stem which is wider than the width of the bore of the handle grip, to support the inner end of the handle grip, and said nut having a sleeve formed thereon 90 engaging closely within the outer end of the bore of the handle grip to support the outer end of the handle grip, said sleeve being tapered toward its entering end, and said entering end being of a diameter substantially the same as the normal diameter of the end of the bore which it enters, so as to spread the walls of the bore and thereby to wedge tightly against the walls of the bore 95 as the sleeve enters the bore.
5. A combined handle and latch for safety cocks made up of a single integral member having means adapted to form a pivotal mounting therefor, said member having a projection extending in one direction from 100 said pivotal mounting comprising means adapted to serve as a latch, said member having a projection extending in another direction from said pivotal mounting comprising means adapted to serve as a stop to 110 limit pivotal movement in one direction, and said member having an extension projecting in still another direction from said pivotal mounting comprising means adapted to serve as a stem for the attachment of 115 a handle grip, and all of said extensions lying substantially in a common plane.
6. A combined handle and latch for safety cocks made up of a single integral member having means adapted to form a pivotal 120 mounting therefor, said member having a projection extending in one direction from said pivotal mounting comprising means adapted to serve as a latch, said member having a projection extending in another direc- 125
- 65 130

tion from said pivotal mounting comprising means adapted to serve as a stop to limit pivotal movement in one direction, and said member having an extension projecting in still another direction from said pivotal mounting comprising means adapted to serve as a stem for the attachment of a handle grip, said last mentioned extension being formed with a shoulder adjacent said pivotal mounting means, a handle grip

mounted upon said stem, and means engaging the outer end of said stem and engaging said handle grip to hold said handle grip in engagement with said shoulder.

In testimony whereof I affix my signature in the presence of two witnesses.

LEO KLEINMAN.
